CLAIM

The ornamental design for a gift box, as shown and described.

DESCRIPTION

FIG. 1 is a front view of a gift box showing our new design; FIG. 2 is a rear view of the gift box; FIG. 3 is a right side view of the gift box; FIG. 4 is a left side view of the gift box; FIG. 5 is a top view of the gift box; FIG. 6 is a bottom view of the gift box; and, FIG. 7 is a top front side perspective view of the gift box. In the drawings, the cross-hatched shading of the ribbon on the gift box indicates a contrast in appearance.
